UNITED STATES PATENT OFFICE.

ARTHUR R. WILFLEY, OF DENVER, COLORADO, ASSIGNEE OF ONE-HALF TO JOSEPH SEEP, OF TITUSVILLE, PENNSYLVANIA.

PROCESS AND APPARATUS FOR ROASTING ORES.

996,548.

Specification of Letters Patent. Patented June 27, 1911.

Application filed October 6, 1910. Serial No. 585,621.

To all whom it may concern:

Be it known that I, ARTHUR R. WILFLEY, a citizen of the United States, residing in the city and county of Denver and State of Colorado, have invented certain new and useful Improvements in Processes and Apparatus for Roasting Ores; and I do declare the following to be a full, clear, and exact description of the invention, such as 5 will enable others skilled in the art to which it appertains to make and use the same, reference being had to the accompanying drawings, and to the letters and figures of reference marked thereon, which 10 form a part of this specification.

My invention relates to a process and apparatus for roasting ores.

This invention is more especially intended for use in producing what is known as a 20 magnetic roast, meaning a roast which shall render the ore magnetic or amenable to the action of magnetism for the purpose of separating the metallic particles from the gangue.

The process, however, consists in employing steam or other suitable moisture-containing fluid for the purpose of completely 25 removing the ore particles from the roasting hearth, the vapor serving at the same time by virtue of its moisture, to check oxidation and thus prevent the possible over-roasting of the ore for purposes of magnetic separation.

In my improved apparatus as disclosed in 35 the drawing, an endless horizontally disposed rotary hearth is employed. As illustrated in the drawing, a nozzle for passing vapor across the hearth in a transverse direction is shown. Of course any suitable 40 apparatus may be employed for accomplishing this purpose. Furthermore, the apparatus includes tanks or jackets through which cooling liquid is constantly circulated, said jackets being located in such 45 proximity to the ore on the hearth as to efficiently perform the function of preventing the over-roasting of the ore during its travel through the furnace.

Another feature of the apparatus is that 50 the space surrounded by the circular traveling hearth is utilized as a chamber into which the roasted ore is removed through the agency of the vapor blast. This space is screen covered for the purpose of preventing the escape of the ore particles while

allowing the escape of any uncondensed vapor and air which may be mingled therewith.

Having briefly outlined my improved process together with a suitable apparatus 60 for carrying out the process, I will proceed to describe the invention in detail, reference being made to the accompanying drawing in which is illustrated an embodiment thereof.

In this drawing: Figure 1 is a top plan 65 view of the apparatus after removing the portion above the section line 1—1 Fig. 4. Furthermore in this view the top of the central chamber is partly broken away. Fig. 2 is a section taken through the feed 70 hopper also cutting the hearth and roasting chamber on the line 2—2 Fig. 1. Fig. 3 is a section taken on the line 3—3 Fig. 2. Fig. 4 is a section taken on the line 4—4 Fig. 1. Figs. 5 and 6 are sections taken on the lines 75 5—5 and 6—6, respectively, of Fig. 1.

The same reference characters indicate the same parts in all the views.

Let the numeral 5 designate a roasting chamber, 6 the endless traveling hearth, 7 80 hangers connected with the hearth and carrying wheels 8 which engage tracks 9 for supporting the hearth. Journaled in the bed or lower part of the masonry 10 is a shaft 12 upon which is mounted a gear 85 wheel 13 which engages a gear 14 secured to the bottom of the traveling hearth. To the outer exposed end of the shaft is made fast a pulley wheel 15 which may be connected by means of a belt with any suitable 90 motor adapted to supply the power for imparting the traveling movement to the hearth.

As illustrated in the drawing, stationary 95 rabbles 16 are mounted in the roasting chamber for the purpose of stirring the ore, whereby its particles are advantageously exposed for roasting purposes. However, if the layer of ore upon the hearth is sufficiently thin, rabbbling may be dispensed with. 100

Heat is supplied to the roasting chamber 5 from a furnace 17 having a grate 18, sufficient fuel 19 being supplied to the grate through an opening 20 normally closed by a door 21. The heat and products of combustion pass to the roasting chamber through an opening 22 communicating with the combustion compartment of the furnace above the grate.

The ore is fed to the hearth from the 110

hopper 23 having a distributing roll 24 below its discharge opening, whereby the ore is evenly distributed upon the hearth as the latter passes below the hopper.

5 Receptacles 25 are passed transversely through the roasting chamber above the hearth and are adapted to receive cooling water, which is circulated therethrough through the agency of pipes 26 and 27, the 10 pipe 27 being provided with a valve 28.

The steam or other moisture-containing vapor is delivered to the hearth through a nozzle 29 connected with a supply pipe 30 having a controlling valve 31.

15 As illustrated in the drawing, a housing 32 covers the hearth and extends inwardly as shown at 33, partly covering a central chamber 34 into which the ore particles 35 are carried as they are removed from the hearth 20 through the agency of the vapor blast. The central portion of the chamber 34 is covered by a screen 36 of suitable mesh to prevent the escape of the ore particles, but at the same time permitting the escape of 25 vapor and air.

In carrying out my improved process, the ore is fed to the endless traveling hearth through the hopper 23, being distributed thereon through the agency of the roller 24 30 in a relatively thin bed or layer.

As illustrated in the drawing, a single nozzle 29 is employed for removing the ore particles from the hearth as the latter rotates. It will, however, be understood that 35 if the hearth is sufficiently large, more than one nozzle may be employed if desired. In other words, the ore may be removed after it has made only a portion of the circuit. However, in case more than one nozzle were 40 employed, more than one feed hopper also would be necessary in order that the hearth might be supplied with ore immediately after its removal therefrom through the instrumentality of the vapor blast. However, the 45 employment of more than one vapor nozzle and more than one feed hopper would be mere duplication, and it has therefore not been thought necessary to illustrate this modification in the drawing.

50 In order to distribute the roasted ore within the chamber 34, deflectors 37 are provided. One of these deflectors is so located that the ore strikes it as soon as it leaves the hearth, under the influence of the vapor blast from the nozzle 29. This deflector is curved to give the ore a sort of whirling action as it enters the said chamber, and this action causes it to strike the second deflector on the opposite side, but with less force. It 55 is believed that the two deflectors will be sufficient to distribute the ore approximately evenly within the said chamber.

The roasted ore may be removed from the central chamber 34 in any suitable manner. It would, of course, be practicable to

make a hole in the wall underneath the circular chamber in which the hearth is located, through which the ore could be dragged out of the chamber by the use of long rakes or by an endless conveyer, as desired. These features are not illustrated as nothing is claimed upon the manner of removing the ore from the said chamber.

Having thus described my invention, what I claim is:

1. The herein described ore roasting process, consisting in subjecting the ore to the action of heat upon a hearth and removing the ore therefrom by a moisture-containing vapor blast.

2. The herein described ore roasting process, consisting in subjecting the ore to the action of heat upon a traveling hearth, and removing the same therefrom through the agency of a moisture-containing vapor blast, for the purpose set forth.

3. The herein described ore roasting process, consisting of subjecting the ore to heat upon an endless traveling hearth, and removing the ore from the hearth at a predetermined point or location in the circuit of travel, substantially as described.

4. The herein described process for producing a magnetic roast, consisting in subjecting the ore to heat upon a revolving hearth and discharging a moisture-containing vapor blast across the hearth, whereby the ore is completely removed from the hearth at a predetermined point or location in its circuit of travel, substantially as described.

5. The herein described ore roasting process, consisting in heating the ore upon a hearth and completely removing the same therefrom by subjecting it to the action of a moisture-containing vapor blast, substantially as described.

6. The herein described ore roasting process, consisting in heating the ore upon a traveling hearth, employing cooling liquid placed in the vicinity of the hearth for properly reducing the temperature, and completely removing the ore from the hearth at predetermined intervals through the agency of a moisture-containing vapor blast, substantially as described.

7. An ore roasting apparatus comprising an ore roasting chamber, an endless traveling horizontally disposed circular hearth located in said chamber, an ore chamber surrounded by the ore roasting chamber, and means for removing the ore from the hearth and discharging it into said ore chamber through the agency of a fluid blast.

8. An ore roasting apparatus including an endless traveling horizontally disposed circular hearth, an ore chamber surrounded by the hearth, and means for removing the ore from the hearth and discharging it into said chamber through the agency of a fluid blast,

said blast being directed crosswise of the hearth, substantially as described.

9. An ore roasting apparatus comprising a circular ore roasting chamber, an ore chamber surrounded by the roasting chamber, and means for removing the ore from the hearth and discharging it into said central ore chamber through the agency of a fluid blast directed crosswise of the hearth, the central ore chamber having a covering composed in part of mesh material sufficiently fine to prevent the escape of ore from the chamber, substantially as described.
10. An ore roasting apparatus comprising a circular roasting chamber, a horizontally disposed traveling hearth mounted in said

chamber, an ore chamber surrounded by the roasting chamber, and means for removing the ore from the hearth and discharging it into the central ore chamber through the agency of a fluid blast directed crosswise of the hearth, the central ore chamber being equipped with curved deflectors for the purpose of distributing the ore in the said chamber, substantially as described.

In testimony whereof I affix my signature in presence of two witnesses.

ARTHUR R. WILFLEY.
